UNITED STATES PATENT OFFICE.

MARTIN FTACNIK, OF CALDWELL, OHIO.

DOOR CLOSER.

Application filed March 27, 1924. Serial No. 702,308.

This invention relates to new and useful improvements in door closers.

An important object of the invention is to provide a swinging door or gate closer which is of exceedingly simple construction and one that may be easily and quickly attached to a door or gate without materially altering the construction of the latter.

A further object of the invention is to provide a closer of the above mentioned type which may be manufactured at a very nominal cost and will thereby constitute a practical article of manufacture.

Other objects and advantages of the invention will be apparent during the course of the following description.

In the accompanying drawing forming a part of this specification and in which like numerals are employed to designate like parts throughout the same:

Figure 1 is a front elevational view of a swinging door and a door opening frame shown in proper relation thereto,

Figure 2 is a transverse sectional view taken upon line II—II of Fig. 1,

Figure 3 is a fragmentary view showing one vertical edge of the door in elevation and the door closer embodying this invention illustrated in vertical section,

Figure 4 is a detail perspective view of the bracket employed for connecting the closer to the door,

Figure 5 is a front elevational view of a wire fence and a gate associated therewith and is intended to illustrate the adaptability of the closer to such a type of fence and gate,

Figure 6 is a transverse sectional view of the closer used in connection with the gate and fence and is taken upon line VI—VI of Fig. 5, and

Figure 7 is a transverse sectional view taken upon lines VII—VII of Fig. 5 and illustrates in detail a latch structure which is adapted to be used in connection with the gate shown in Fig. 5.

In the drawing, wherein for the purpose of illustration is shown a preferred embodiment of this invention, the numeral 5 designates the casing or frame which surrounds the opening provided for a door. In Fig. 2 the vertical side portion 5^a of this frame is illustrated in transverse section and is shown as consisting of the opposite face boards 6 which are connected by the cross board 7. This cross board is illustrated as

being provided with a rearwardly extending flange 8 which has one of its faces on a plane with one wall of a slot 8' that is formed in the cross board 7. In Figs. 1 and 2, the various portions of the frame 5 are illustrated as being provided with stop strips 9 which are employed for preventing too great a movement of the door 10 in one direction, or in other words, the stop strip 9 will retain the door in its properly closed position.

In Figs. 1, 2 and 3, the vertical edge portion 10^a of the door 10 is illustrated as being provided with the cutout portions or notches 11 which extend inwardly from the vertical edge of the said door. In Figs. 1 and 3, this vertical edge of the door is illustrated as being provided with elongated recesses 12 which communicate at their adjacent ends with the cutout portion or notch 11 and extend upwardly and downwardly from opposite sides thereof. In Fig. 4, there is illustrated in detail an angular bracket which consists of the central portion 13 and the end portion 14. These portions 13 and 14 are each provided with a pair of spaced apertures 15, the purpose for which the same are to be used will be described at a later point. In Fig. 3, the bracket illustrated in detail in Fig. 4 is shown as being secured to the vertical portion 10^a of the door 10 by means of the screws 16 which pass through the openings 15 formed in the end portions 14 of the bracket and these said screws 16 hold the end portions 14 in the elongated recesses 12 formed in the said door 10. The embedding of these end portions 14 in the elongated recesses 12 will position the central portion 13 of the bracket well within the cutout portion 11. In Figs. 1 to 3 inclusive, there is illustrated a coil spring 17 which has its end 18 secured by rivets or the like to the flange 8 carried by the cross board 7 of the door frame portion 5^a. The opposite end 19 of the coil spring 17 is secured to the central portion 13 of the bracket illustrated in detail in Fig. 4 by suitable rivets which pass through the openings 15 formed in this central portion 13. This coil spring 17 is also illustrated as having a plurality of coils or turns which are arranged around the central portion 13 of the bracket. By inspecting Fig. 1, it will be seen that the structure illustrated in Figs. 2 to 4 inclusive have been provided in duplicate and arranged in prox-

imity to the hinges 20 which swingingly connect the door 10 to the portion 5^a of the door opening frame 5. It will also be seen that when the door 10 is swung into its open position upon the hinges 20 that the coil spring 17 will be tightened around the central portion 13 of the bracket illustrated in detail in Fig. 4. This tightening of the coil spring 17 will cause the door 10 to assume a closed position as soon as it is released by the person who caused the door to be opened.

In Figs. 5 to 7 inclusive there is illustrated a further adaptation of the closer illustrated in Figs. 1 to 4 inclusive. There is illustrated in Fig. 5 a portion of a wire fence which consists of the posts 21 and 22 which constitute opposite sides of a gate opening. These posts 21 and 22 are preferably of tubular formation and may consist of pipe sections. Secured to these posts 21 and 22 are the wires 23 which form a part of the fence illustrated. There is also illustrated a gate 24 consisting of the tubular frame 25 that is hingedly connected, by the hinges 26 to the post 21. This frame 25 is provided with suitable strands of wire 27 which close the space between the various portions of the frame 25. In Fig. 6 there is illustrated a transverse sectional view of the gate and fence and shows a coil spring 28 which is secured at one end to the post 21 by the rivets 29 and is secured at its other end to one of the vertical sides of the frame 25 by means of the rivet 30. It will be noticed that this coil spring 28 is partially wound around the frame portion of the gate 25 and that when the gate is swung open on the hinges 26, the coil spring will be tightly wound around the frame portion 40 of the gate and will cause the latter to swing into its closed position after being released by the person opening the same.

In Fig. 7, there is illustrated a latch bar 31 that is pivotally secured to the frame 25 of the gate 24 by means of the rivet 32 and

is prevented from dropping below a horizontal plane by the stop element 33 which is carried by the gate frame below the rivet 32. This latch bar 31 is further provided with a cross pin 34 which is intended to be used as a handle for operating the said bar. The post 22 of the fence is provided with a latch or keeper 35 which is rigidly secured to the said post by the rivet 36.

It is now believed that the construction of the various elements illustrated in the accompanying drawing will be understood from the above detail description. It is, also, to be understood that the forms of this invention herewith shown and described are to be taken as preferred examples of the same, and that various changes in the shape, size, and arrangement of parts may be resorted to without departing from the spirit of the invention or the scope of the subjoined claim.

Having thus described the invention, I claim:—

In a device of the type described, the combination with a hollow doorway frame having a slot formed in one vertical side portion and a flange within the bore of said side portion juxtaposed to said slot, and a door hingedly connected to said frame and having in its hinged edge a cutout portion 75 horizontally aligned with said slot and elongated recesses above and below and communicating with said cutout portion, of an angular bracket comprising end portions secured in said recesses and an offset central portion located in said cutout portion and out of contact therewith, and a strap spring having one end coiled around and secured to the offset central portion of said bracket and the other end threaded through said 80 slot and secured to the flange of said vertical side portion.

In testimony whereof I affix my signature.

MARTIN FTACNIK.
